FLAT-BANK CROSSBAR SWITCH

Edwin L. Earle, Chicago, Ill., assignor to International Telephone and Telegraph Corporation, New York, N. Y., a corporation of Maryland

Application July 27, 1955, Serial No. 524,632

3 Claims. (Cl. 179—27.54)

This invention relates to a flat-bank crossbar switch such as is used in automatic telephone systems and elsewhere. The principal object of the invention is to provide an improved construction for the contact bank and for the crosspoint-actuating mechanism of the noted type of switch which simplifies the adjustment procedure while avoiding the likelihood of undesired circuit closures by crosspoint contact members in their normal relaxed position.

The flat-bank crossbar switch is exemplified by the United States Patent No. 2,577,067, issued December 4, 1951. In such a crossbar switch, the flexible contact members of the stacks used at the crosspoint extend parallel to the plane of the switch frame, rather than at right angles thereto, thus enabling the horizontal multiple, in addition to the vertical multiple, to be built in as a part of the bank construction.

Heretofore, the crosspoint contact members of the contact bank of such a switch have required careful adjustment to insure their effective opening on release while preventing retraction to an extent sufficient to make unwanted metallic contact with the fixed contact members associated with the underlying flexible contact members. Moreover, a rather expensive backstop arrangement external to the contact bank has been required to maintain the crosspoint actuators, or ladders, at a common level for free crosspoint selection with a minimum of lost actuating movement.

According to the invention, the two foregoing difficulties have been simply and economically overcome by widening certain of the insulating strips already required in the several clamping assemblies to preclude the unwanted metallic contact of released flexible contact members, which provides an insulated surface which serves the dual purpose of (1) preventing unwanted electrical contact, and of (2) providing a definite stopping position for the actuating ladders. Preferably, the flexible contact blades have no definite opening tension formed therein, and the required opening tension is supplied by a separate spring blade overlying each stackup.

The above-mentioned and other features and objects of this invention and the manner of attaining them will become more apparent, and the invention itself will be best understood, by reference to the following description of an embodiment of the invention taken in conjunction with the accompanying drawings comprising Figs. 1 to 3, wherein:

Fig. 1 is a top view of a switch embodying the invention;

Fig. 2 is a sectional view, taken along line 2—2 of Fig. 1; and

Fig. 3 is a partial sectional view similar to Fig. 2, showing a modified construction.

Figs. 1 and 2

Referring first to Fig. 1, the improved crossbar switch shown therein comprises a contact bank providing the desired number and arrangement of stackups, together

with a rectangular structure for supporting the contact bank and controlling the desired actuation of the stackups thereof. The rectangular structure may be constructed generally as is disclosed in the noted patent. Such a structure includes front and rear members 1 and 3, and left and right frame members 2 and 4 suitably secured thereto through corner gussets 5 and 6, six horizontal select shafts, S1—2 to S11—12, pivotally mounted between shaft brackets 18 and 19, a desired number of vertical bars or hold-magnet armatures 90, pivotally mounted between front and rear members 1 and 3, and a contact bank providing stackup comprising vertical rows overlying the respective armatures 90, the contact bank being supported on channels 25.

The front frame member 1 is provided with an inwardly extending upper flange. The rear member 3 is a similar structure, but with an inwardly extending lower flange added. The upper flanges of both members serve as mounting supports for members 25 while the lower flange on rear member 3 serves as a mounting support for hold-magnets 80.

Shaft brackets 18 and 19, extend across the switch frame at the ends, and are suitably secured to corner gussets 5 and 6. These brackets support the select shafts S1—2 to S11—12, and their associated select magnets M1 to M12 as described more fully in the noted patent.

Channels 25 are secured to the upper flanges of front rear members 1 and 3 by screws 26. Elongated apertures 221 permit channels 25 to be adjustably aligned. Each clamping stackup 150 is secured to a channel 25 by screws 153 which pass through the stackup and are threadedly engaged in tapped holes 27. Pilot holes 29 are provided in channels 25 which may be used during assembly of the bank for alignment of the parts.

A hold-magnet 80 and associated armature 90 are provided for each vertical row of contact stackups. Hold magnets 80 are adjustably mounted upon the lower flange of rear frame member 3 below and slightly to the left of their associated stackups. Armature 90, extending from rear frame member 3 to front frame member 1, are pivotally mounted at each end to permit their rotation to actuate selected stackups of contacts.

Mounting tab 93 of armature 90 is pivotally secured to the rear frame member 3 by bearing pin 109 and is pivotally secured to the front frame member 1 by adjustable armature leveling plate 112. As disclosed in the noted patent, the exposed face of the front member 1 is provided with elongated openings to receive an adjustable armature leveling assembly which is secured thereto by a screw. The leveling assembly includes a bearing screw 206 which is threaded through plate 112 to engage armature mounting tab 93 to support and to provide lateral adjustment of armature 90. A slot in the end of bearing screw 206 facilitates this adjustment and locknut 209 locks the bearing screw in its adjusted position. Armature 90 is readily removed by loosening locknut 209, backing out bearing screw 206, disengaging bearing pin 109 and dropping the armature out of the switch structure.

The armature 90 comprises a tractive portion 91 which overlies the upper end of the core of its associated hold-magnet 80 and a laterally extending main portion 92 which carries pivotally secured select levers 220. The main portion 92 has its edge portion 94 turned up to provide a more rigid structure. An adjustable platform 95 is provided for each pair of adjacent crosspoints, being integrally connected with the main portion 92 by arms 96. Each structure 95 includes a recess 213, the sides of which engages the select-lever downwardly extending tab 219 (Fig. 2) to provide a stop position for select lever 220.

The construction of the contact bank supported on

channels 25, to provide the vertical and horizontal rows of selectively operable contact members is as generally disclosed in the principal embodiment of the noted application.

Each vertical row of stackups comprises ten principal stackups (first ten, counting from the front rail) and two extension stackups (the eleventh and twelfth). As disclosed in the noted patent, each principal stackup (see Fig. 2) has six contact pairs.

The contact bank comprises a unitary structure in that the vertical and horizontal conducting strips 157 and 140, assemble together to provide stackups, extend entirely through the bank at respective intersecting directions. Such strips are in alternate layers, and are maintained in assembled position by clamping pile up 150, one for each support channel 25.

As shown best in Fig. 2, each clamping pile up 150 comprises layers of conducting members, interspersed with insulator strips 154 and 160, clamped between an upper clamp strip 151 and a cross-support channel 25, by screws 153 which pass through the pile up.

Each clamping pile up 150, except the starting one (at the left of the switch), includes six conducting strips 157 common to the stackups comprising the vertical row immediately to the left. As disclosed in the noted patent, such strips serve as a common multiple for the six contact members of all stackups in that vertical row, for the leftwardly overhanging portion of the conducting strips 157, carry the fixed contact members. Each conducting strip 157 is wider than the insulator strips 154, and has an overlying insulator 160 which may be of the general configuration as conducting strips 157. Each such strip 157 has a row of contact points fixed to the lower side of the overhanging left-edge portion for cooperation, in pairs, with contact points fixed to the upper side of the flexible traveling springs 161. The overhanging edge portion of each conducting strip 157 and its associated overlying insulator 160 may be notched between the contact points as is disclosed in the noted patent to facilitate observation of the contact points.

As seen best by a comparison of Fig. 1 with Fig. 2, each clamping pile up 150 preceding the last, clampingly supports the base portion of the flexible contact springs 161 of the stackups comprising a vertical row. Any such contact spring 161 extends to the right to the vicinity of the next succeeding clamping pile up 150, with its free end cooperatively underlying the overhanging left edge portion of the associated vertical multiple strip 157, secured in the next succeeding clamping pile up.

It will be observed that two clamping pile ups are required for the first vertical row of stackups, the first to support the base portion of the flexible contact spring, and the second to support the vertical conducting strips comprising the six contact members of the vertical row of stackups. For each vertical row of stackups exceeding the first, only a single clamping pile up is required. Each clamping pile up between the first and last, supports contact elements for the vertical rows of stackups for the immediately preceding vertical row, and the traveling spring contact elements for the immediately succeeding vertical row of stackups.

To facilitate spacing, the first vertical row of stackups (to the left as viewed in Fig. 2) is provided with dummy conducting strips 157', being of the same thickness as conductor strips 157. Insulators 160', similar to insulators 160 may be of a reduced width except the lowermost insulator 160 which is of an increased width to prevent the overlying terminal members 170 from contacting channel 25.

Traveling blades 161 (Fig. 1) may be formed as disclosed in the noted patent including their integral horizontal multiples 140. The left portion of the strip is provided with a terminal 170 extending beyond the stackup 150 to facilitate external connection with the bank.

Each stackup 150 (except the last) includes an upper

guide comb 45, underlying clamping plate 151. Each upper comb 45 includes blades 46 extending from the stackup and overlying each traveling blade 161 and having an aperture 47 for receiving the upper reduced portion 133 of actuating ladder 132. Each stackup 150 also includes a lower guide comb 48 having underlying blades 49 for engagement with the lower notched portion of ladder 132 to prevent rotational movement from its illustrated position.

10 Each traveling blade 161 is provided with an aperture for receiving actuator 132 which can pass therethrough edgewise. These actuating studs are conveniently assembled with its stackup by passing it downward through the slot in the spring from above the contact bank before 15 comb 45 is assembled, and then moved forward (to the left as viewed in Fig. 2) until the actuating portion 136 of ladder 132 engages the under surface of its associated spring 161, blade 49 of lower comb 48 then engages the lower edge of actuating stud 132. The upper 20 end of the stud has a reduced portion 133 which enters an aperture 47 in blade 46 to hold the top of the stud in its illustrated forward position. When desired, the stud 25 132 may be removed by disengaging the upper and lower comb blades 46 and 49 and moving the stud to the right (as viewed in Fig. 2) and upward out of the stackup.

To simplify adjustment of the contact bank, blades 46 of upper comb 45 are tensioned downwardly to position the free ends of contact blades 161 associated therewith in engagement with an underlying insulator 160, 30 when in its normal relaxed position. This eliminates the expensive preforming operation of the traveling blades 161 or the individual adjustment of blades 161 after the bank has been assembled to insure the unwanted metallic contact with the fixed contact member 157 35 associated with the underlying flexible blades or channel 25. The lower comb 48 is of relatively thin-flexible material and blades 49 prevent studs 132 from tilting out of their illustrated normal position.

Selection of the first horizontal row of stackups, for 40 example, occurs responsive to the energization of the select magnet M1. The underlying wing of the associated armature, as disclosed in the noted patent, is thereby attracted upwardly into engagement with the magnet M1 whereby the first select shaft S1-2 is rotated 45 in a counterclockwise direction. Thereupon select levers 230 of shaft S1-2, one for each vertical row of stackups, are tipped toward a position underlying the first horizontal row. In each idle vertical row of stackups (at which the hold armature 90 is in a normal position), 50 arm 130 of select lever 230, engages select lever 200 at its mid-portion 218, to serve as a yielding drive means effective to drive the associated select lever, unless restrained, in one of its three positions (its normal position is as shown in Fig. 1 or to a position underlying the first or second stackup) in response to the rotation of the select shaft in the corresponding direction. Select levers 220 55 are rotatably secured to portion 92 of armature 90 by means of shoulder rivets 216 which are received in apertures 215. The select levers 200 are shown to comprise 60 generally a T-structure lying in the horizontal plane.

Select levers 220, formed of sheet metal, has two raised platforms 217 and a downwardly extending stop tab 219 (Fig. 2). The portion of the select lever 220 including elevated platforms 217 is raised to a level whereby it rests 65 flatly on raised portion 95 of the armature.

When the select lever is positioned beneath the selected stackup by rotation of its associated select shaft providing the hold-magnet armature is in its normally unoperated position, raise platforms 217 are positioned underlying 70 the associated actuated stud 132.

Downwardly extending tab 219 lies within the recessed portion 213 and is flanged so as to underlie the hold-magnet armature portion 95 to prevent any upward movement of the select lever unless accompanied by its associated armature 90. When the select lever is moved in

either direction for its selecting action, tab 219 engages the sides of the recess 213 to provide stop portions so that the select lever properly underlies its associated selected stackup.

When the selecting lever is moved from its normal position to one of its two selecting positions in response to the select shaft rotation, raised portion 217 underlies the downwardly extended tab portion 134 of actuating stud 132 whereby the energization of hold magnet 80 associated with any idle vertical row of contact stackups causes tractive portion 91 to be attracted downwardly into engagement with the core of hold magnet 80, rotating armature 90 about its pivotable mounting arrangement previously described. This rotating action raises portion 95 of armature 90 with all its selecting levers 220. Select lever portion 217 engages the reduced portion 134 of stud 132 associated with the noted first stackup causing it to upwardly carry its associated stackup traveling spring 161 into engagement with its associated fixed contacts.

When the armature stroke is only partially completed, the traveling springs 161 of the noted first stackup engage their associated overlying fixed contact members 157. The final portion of the movement of the armature 90 causes the traveling springs to bow as contact pressure increases. The hold magnet 80 is maintained energized as long as the connection established is to remain intact. The select magnet M1 to M12 may be deenergized immediately as disclosed in the noted patent whereby the operated select shafts are returned to their unoperated position, the select levers 220 associated with the unoperated hold magnet armatures are returned to their normal position. The lever 220 associated with the operated armature 90 is maintained in its selected position by the downward pressure exerted on it by the traveling springs 161 and the blade 46 of the actuated stackup. The arm of the select finger 130 remains in its selected position and flexes as the select shaft is returned to its normal position. The select finger is returned to its normal position when hold magnet 80 is deenergized.

When hold magnet 80 is deenergized when the connection is released, armature 90 rotates back to its normal position against back stop screw 115. The back stop position of armature 90 is readily adjusted by loosening locknut 116 and rotating the adjusting screw 115 to the desired setting whereby locking screw 116 is then tightened. A residual clip 117 is provided, as shown in Fig. 2, and is attached to the tractive portion 91 of armature 90 to eliminate any undesirable individual magnetism.

To facilitate armature leveling, platforms 95 are provided, one for a pair of adjacent stackups; for example, a platform 95 for the stackups associated with select lever S1-2. This may be readily done by bending arms 96, thereby leveling platform 95 to position its associated select lever 220 with its overlying stud 132.

Modified comb construction—Fig. 3

Referring to Fig. 3, the construction of a modified lower guide comb for the stackup actuators will be described. The modified guide comb 48' may be formed of relatively thin-flexible material having blades 49' underlying each stackup.

The flange portion of channel 25 is provided with several off-set portions 40 (only one of which is shown) which are received within apertures in comb 48' to position the comb thereon. The comb may then be rigidly secured to the flange as by spot-welding or riveting over the off-set portions 40.

A modified actuator stud 132' has a reduced lower portion 134' which is received within aperture 50 of blade 49' to position the lower end thereof.

While I have described above the principles of my invention in connection with specific apparatus, it is to be clearly understood that this description is made only

by way of example and not as a limitation to the scope of my invention.

I claim:

1. A contact bank comprising a succession of upstanding stackups of contact members arranged in a row to provide a longitudinal row of multi-conductor switching groups equal to one less than the number of said stackups, with each switching group including flexible contact members supported by one stackup and extending forwardly into cooperative underlying relationship with respective fixed contact members supported by the next succeeding stackup, each stackup including interspersed contact members and insulating sheets and means clamping them together, each intermediate stackup having clamped therein the base portions of the flexible contact members which extend forwardly therefrom, with each overlaid by a fixed contact member which extends rearwardly from the stackup for cooperation with a flexible contact member supported by the next preceding stackup, each fixed contact member in any stackup succeeding the first being immediately underlaid by an insulating sheet which is sufficiently narrow to provide room under the rearwardly extending portion of such member for the free end of the cooperating flexible contact member held by the preceding stackup to be moved into and out of contact with the fixed member, the last said insulator in any intermediate stackup being underlaid by the clamped base portion of a flexible contact member, any last said clamped base portion being underlaid by an insulating sheet which is widened to provide a portion which extends rearwardly to underlie the free end of the corresponding contact member which extends forwardly from the next preceding stackup, whereby a definite insulated stopping barrier is provided for each flexible contact member of the switching group in its open, or relaxed, condition, each last said insulator above the lowermost one in the stackup overlying a fixed contact member and barring contact therewith by the free end of the flexible contact member which lies above it.
2. In a contact bank according to claim 1, a separate vertically disposed actuator for each switching group engaging the flexible contact members thereof near their free end and arranged and adapted to impel each associated flexible contact member upwardly and downwardly responsive to respectively corresponding movement of the actuator, separate restoring-spring means for each actuator external to the said contact members associated therewith normally urging the actuator downwardly to bring the free end of the contact members into engagement with their said underlying insulating sheets.
3. In a contact bank according to claim 1, each said stackup being extended laterally of the said row in which they are arranged and having additional contact members similarly clamped between the insulators thereof to provide additional and similar longitudinal rows of multi-conductor switching groups, lateral multiple conductors extending laterally along, and supported by, each said stackup beyond the first and interconnecting in common corresponding contact members in the several longitudinal rows of switching groups, and longitudinal multiple conductors extending along the respective longitudinal rows of switching groups through the said stackups and between the said insulators thereof to interconnect in common corresponding contact members in the several lateral rows of switching groups.
